FUZE SAFETY DEVICE

Charles R. Hamilton, Socorro, N. Mex., assignor to the United States of America as represented by the Secretary of the Navy

Application August 25, 1950, Serial No. 181,479

4 Claims. (Cl. 102—79)

The present invention relates to an improved contact fuze for an explosive projectile.

More particularly the invention relates to a novel safety device and arming mechanism for a contact fuze.

Much trouble has been experienced with accidental explosions in the storage and handling of projectiles which utilize contact fuzes. Because it was impossible always to control the manner in which the fuzes would be handled, the need arose for a safety device that would prevent accidental explosions of the main charge of a projectile, but which nevertheless would assure proper operation upon coming in contact with a target. The fuze safety device which constitutes the present invention was developed to meet this need.

Broadly, this device consists of a gate which interrupts the powder train between the detonator and the booster charge, and which prevents the booster, and therefore the main charge of the projectile, from exploding should the firing pin mechanism be tripped prematurely. Upon the projectile being fired from a gun, the gate moves out from between the detonator and the booster charge and reestablishes the powder train to the main charge. In order to maintain the gate in the latter position, and thereby assure proper operation of the exploding mechanism upon impact with a target, the fuze safety device further incorporates a novel locking mechanism which serves to maintain the safety device in the armed position even under severe laterally applied forces, such as would occur should the shell strike an object with a glancing blow before hitting the target.

It is therefore one object of the present invention to provide a contact fuze for explosive projectiles which will prevent accidental explosions of said projectiles while being handled.

Another object of the invention is to provide a safety contact fuze for an explosive projectile which will move to armed position, upon the firing of the projectile.

Other objects and many of the attendant advantages of this invention will be appreciated readily as the same becomes understood by reference to the following detailed description, when considered in connection with the accompanying drawings, wherein:

Fig. 1 is a fragmentary view, partly in axial section, of a projectile having a contact fuze, which includes the improved safety device;

Fig. 2 is a cross-section, in the plane 2—2 of Fig. 1, showing the improved safety device in the armed position;

Fig. 3 is a cross-section similar to Fig. 2 but showing the improved safety device in the unarmed position;

Fig. 4 is a longitudinal section taken in the two planes indicated by line 4—4 of Fig. 2, showing the improved safety device in the armed position; and

Fig. 5 is a longitudinal sectional view taken in the two planes indicated by line 5—5 of Fig. 2 and showing the auxiliary locking means.

2

Referring now to Fig. 1 of the drawings, there is shown for completeness the forward end of a projectile 2, slightly broken away, which has a threaded cylindrical after portion 3. Projectile 2 has therein a forward chamber 4, a central chamber 5, and a rear chamber 6, said chambers having their longitudinal axes coincident with the longitudinal axis of said projectile, and being of progressively greater diameters. Mounted in the smaller forward chamber 4 is a spring actuated firing pin mechanism 7 having an actuating pin 8 coincident with the longitudinal axis of said projectile and poised to strike rearward into central chamber 5 after the projectile strikes an object. The preceding features, however, constitute the subject matter of U.S. application 15 for patent, Serial No. 37,136, now Patent No. 2,701,527, filed by L. P. Granath and S. S. Podnos, July 6, 1948, for a "Selective Delayed Action Fuze," and form no part of the present invention, and hence are not discussed further herein.

20 Situated in central chamber 5 is a fuze safety device that embodies the present invention. This device is described more fully hereinafter; at present, for the purpose of illustrating its function, it may be explained merely that in the armed position, the device serves to 25 establish a continuous powder train between a detonating charge exposed to the action of firing pin 8, and a booster charge 9 contained within the rear chamber 6.

For a detailed description of the fuze safety device, reference is now made to Figs. 2 through 5 of the drawings. Referring first to Fig. 4, the safety device comprises a housing A which includes a pair of cylindrical blocks 10 and 12 that are separated by a partition 14, said blocks and partition being suitably secured together, as a plurality of rivets 15, and 15a, as seen in Figs. 2 35 and 3. An axially located orifice 16 is provided in the partition 14, for a purpose that is explained below. The forward block 10 has a centrally disposed cylindrical chamber 17, and mounted in this chamber is a detonator 18 containing a percussion explosive, such as tetryl lead.

40 The chamber 17 is axially aligned with a second chamber 21 formed in the rearward portion of block 12, and which carries the percussion explosive 9 constituting a portion of the booster charge of the projectile. When the parts are in the armed position, chamber 17 communicates through the central orifice 16 in partition 14

45 with a third chamber 23 that, as is best shown in Fig. 2, is formed in a generally semi-circular rotor 26, turning about an axis eccentric to that of the projectile. Referring again to Figs. 2, 3 and 4, it will be seen that 50 rotor 26 is positioned in a relatively large, off-center, cylindrical chamber 27 formed in the forward face of block 12, and is pivoted about a shaft 28. Chamber 23 contains a percussion explosive pellet 24, which may be rotated in and out of axial alignment with chambers 17 and 23.

55 Thus, as is best shown in Fig. 3, when in unarmed position, rotor 26 acts as a movable barrier or gate preventing an accidental explosion of the detonator 18 from traveling to the main explosive charge of the projectile.

60 Upon firing the projectile in which the device is mounted, the heavy end of the gate or rotor 26 is swung outward by centrifugal force, due to projectile spin, to the armed position shown in Fig. 2. One of the rivets, 15a, may be placed as shown in Figs. 2 and 3, to act also as a 65 stop for positioning the gate or rotor 26 in "armed" position, when engaged by a corner of said rotor, as shown in Fig. 2. In this position, explosive pellet 24 is aligned with detonator 18 and charge 9, thus establishing a powder train from said pellet 24, which is designed and positioned to be acted upon by the firing pin 8 to the main explosive charge of the projectile.

In order to assure proper operation of the contact fuze

upon impact with a target, the safety device incorporates a novel locking mechanism which prevents the gate or rotor 26 from pivoting chamber 23 out of alignment after the projectile has been fired. With reference to Fig. 2, this mechanism comprises a bore 29 formed in rotor 26, and extending inwardly from the curved surface of the rotor toward chamber 23. Bore 29 has a further axial extension bore 30 of a smaller diameter extending inwardly toward chamber 23 and forming a shoulder 32. As is best seen in Fig. 3, in the unarmed position, shoulder 32 supports a detent 34 having a slender stem 36 that projects into bore 30. When the rotor 26 is turned to the armed position, as illustrated in Fig. 2, detent 34 slips into an orifice 38 that then is aligned with bore 29, and that extends from the cavity 27 through block 12 to its outer surface.

To supplement the locking action of detent 34, the safety device further includes an additional locking stop means for retaining rotor 26 in the armed position. Referring to Fig. 5, this stop means includes a longitudinally extending bore 39 formed in the rearward face of rotor 26. In the armed position, bore 39 is aligned with a similar bore 40 that is formed within recess 27 in the forward face of block 12, and that contains a cylindrically shaped, freely slideable slug 41. Thus, should the projectile in which the arming mechanism is mounted strike an object with a lateral or glancing blow, slug 41 slides forward into bore 39, thereby locking rotor 26 in the armed position. This locking arrangement is independent of and supplementary to the locking action of detent 34.

Referring again to Fig. 3, gate or rotor 26 is retained in the unarmed position by a primary, cross-shaped detent 42 having a pair of tapered wings 49. The inner end of primary detent 42 fits into a rectangular notch 43 cut in the periphery of rotor 26, and said detent is slidably supported in a first, radially extending groove 44 formed in the forward face of block 12, with the wings of the detent extending into a second, chordally disposed, transverse groove 46. Transverse groove 46 is also formed in the forward face of block 12, and intersects groove 44 at right angles.

The inclined surfaces of the tapered wings 49 of detent 42 bear against the supplementary inclined surfaces 48 of a pair of secondary detents 50 which are slidably mounted in the transverse groove 46, and urged toward primary detent 42 in a wedging action, which is produced by a pair of coiled springs 52 acting against a pair of fixed blocks 54 mounted in the respective ends of the groove 46, and which is sufficiently strong to maintain detent 42 depressed into rectangular notch 43 even under severe shocks, such as would occur if the assembly were accidentally dropped from a considerable height while being handled.

While the operation of the invention will presumably be clear from the structure disclosed, it may be well to summarize it briefly as follows: With reference to Fig. 3, when the projectile in which the fuze is mounted is fired, and acquires spin, the secondary detents 50 move out by centrifugal force, against springs 52, releasing the primary detent 42, which then moves radially outward and unlocks rotor 26. Rotor 26 then turns, due to centrifugal force, as already explained, toward the armed position shown in Fig. 2, and aligns chamber 23 with detonator 18, radial bore 29 with orifice 38, and bore 39 with bore 40. When bore 29 is properly aligned with orifice 38, the detent 34 moves outward and enters said orifice 38 to lock rotor 26 in the armed position. As soon as the detent 34 has thus moved outward to its locked position, stem 36 of the detent falls clear of the axial bore extension 30 and misaligns the axis of detent 34 and that of the bore 30. Any inward motion of the detent occurring thereafter will merely bring the end of the stem 36 into contact with shoulder 32, thereby making

it extremely improbable that a large lateral force will cause disengagement of the detent from the orifice 38.

Referring now to Fig. 5, should the projectile be subjected to a laterally applied force by the projectile striking an object with a glancing blow before the firing pin is actuated, cylindrical slug 41 in bore 40 moves forward into bore 39 to supplement the locking action of detent 34. The combined action of detent 34 and slug 41 thereby assures proper operation of the fuze when the firing pin mechanism is actuated.

Obviously many modifications and variations of the present invention are possible in the light of the above teachings. It is therefore to be understood that within the scope of the appended claims the invention may be practiced otherwise than as specifically described.

What is claimed is:

1. A safety device for a projectile fuze, including a cylindrical housing having therein an off-center chamber and having a passage extending substantially radially from said chamber through said housing, a detonator and an explosive charge secured axially in opposite ends of said housing, a gate pivotally mounted within the chamber and initially interposed between the detonator and the explosive charge, said gate having a chordally-directed bore therein that may be brought substantially into register with the said passage, said bore having at its inner end an extension of reduced diameter with a shoulder between the bore and the extension, a detent housed in said bore, and having a stem at its inner end fitting into said extension, said detent being movable partly out of the bore when said bore is in register with the passage for locking the gate to the housing, said stem being engageable with said shoulder to prevent subsequent retraction of the detent, said gate carrying an explosive pellet so placed that it is substantially aligned with the detonator and the explosive charge when the detent is thus engaged.

2. The combination defined in claim 1, with additionally the feature that in the initial position of the gate its center of gravity lies closer to the axis of the projectile than the pivot of said gate so that centrifugal force will cause the gate to rotate about its pivot, when projectile spin exists, to cause the detent to become engaged in the passage.

3. A safety device for a projectile fuze, including a housing having an off-center chamber formed therein, a detonator and an explosive charge, secured axially in the housing at opposite ends of the chamber, a pivotally mounted gate in the chamber and initially interposed between said detonator and said charge, an explosive pellet mounted in said gate, the gate being rotatable from its initial position to a second position by centrifugal force to interpose said pellet between the detonator and said charge, said gate having a chordally directed bore therein with a shorter, smaller-diameter bore at its inward end, forming a shoulder at the junction of said bores, a detent having a body portion guided by and fitting slidably in the larger bore and having a stem extending from the inward end of said body portion and projecting into the smaller bore, the housing having an aperture therein placed to register with the larger bore when the pellet is aligned between the detonator and the explosive charge, whereby due to centrifugal force the outer end of said detent will enter said aperture when such alignment exists whereby the stem will be withdrawn from the smaller bore and will lodge against the shoulder, preventing the full return of the detent into the bore and thus locking the gate against rotation.

4. A safety device for a projectile fuze, including a housing having an off-center chamber formed therein, a detonator and an explosive charge secured axially in the housing at opposite ends of the chamber, a gate pivotally mounted in the chamber and initially interposed

between said detonator and said charge, an explosive pellet mounted in said gate, the gate being rotatable from its initial position to a second position to interpose said pellet between the detonator and the explosive charge, said housing having an orifice extending substantially radially from said chamber, said gate having a chordally directed bore that is in substantial registry with said orifice when said gate is in said second position, said bore having at its inner end an extension of reduced diameter with a shoulder between said bore and said extension, a detent housed in said bore and having a stem at its inner end fitting into said extension, said detent being movable by centrifugal influences partly out of the bore and partly into said orifice when said gate is in its second position for locking said gate to the housing, said stem being engageable with said shoulder to prevent a subsequent retraction of said detent, a pri-

mary detent mounted in said housing and operable to hold said gate in its initial position, secondary detent means operable to restrain said primary detent from accidental operation, said primary detent and said secondary detent means being releasable by centrifugal influences to free said gate for movement to the armed position.
